DESIGN FOR A COMPACT OR SIMILAR ARTICLE

Sigmund Dawer, New York, N. Y.

Application October 3, 1942, Serial No. 108,424

Term of patent 7 years

To all whom it may concern:

Be it known that I, Sigmund Dawer, a citizen of the United States of America, residing in New York city, county of New York, and State of New York, have invented a new, original, and ornamental Design for a Compact or Similar Article, of which the following is a specification, reference being had to the accompanying drawing, forming part thereof, wherein, showing a slot through which a photograph may be inserted.

I claim:

The ornamental design for a compact or similar article, substantially as shown, and described.

SIGMUND DAWER.
